DESIGN.

H. HUNT.

CARPET.

No. 18,162.

Patented Mar. 6, 1888.

UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 18,162, dated March 6, 1888.

Application filed January 26, 1888. Serial No. 262,098. Term of patent 3½ years.

To all whom it may concern:

Be it known that I, HENRY HUNT, of Greenville, New Jersey, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

My design consists of flower and leaf forms arranged upon a rather prominent stem-work in a more or less open manner. The larger flower forms are circular in shape and have

a central portion surrounded or encircled by radial pointed leaves. There are smaller circular flowers scattered here and there among the leaves. The leaf forms are, for the most part, long and narrow, though a few broad leaves appear at the bottom and the top of the design. Several small buds hang from the stems, and at the upper end of the most prominent stem is a large bud or blossom, partly opened.

What I claim as new, and desire to secure by Letters Patent, is—

The design for carpets, consisting of the design substantially as shown.

HENRY HUNT.
